US0D1028860S

(12) **United States Design Patent** (10) Patent No.: **US D1,028,860 S**
(45) Date of Patent: ** May 28, 2024

(54) **TIRE FOR MOTORCYCLE**

(71) Applicant: **SUMITOMO RUBBER INDUSTRIES, LTD.**, Kobe (JP)

(72) Inventor: **Ryosuke Morimura**, Kobe (JP)

(73) Assignee: **SUMITOMO RUBBER INDUSTRIES, LTD.**, Kobe (JP)

(**) Term: **15 Years**

(21) Appl. No.: **29/849,200**

(22) Filed: **Aug. 9, 2022**

(51) LOC (14) Cl. **12-15**
(52) U.S. Cl.

USPC **D12/535**

(57) **CLAIM**

The ornamental design for a tire for motorcycle, as shown and described.

DESCRIPTION

FIG. 1 is a front perspective view of a tire for motorcycle showing my new design;

FIG. 2 is a front view thereof;

FIG. 3 is a left side view thereof;

FIG. 4 is a rear view thereof;

FIG. 5 is a right side view thereof;

FIG. 6 is a bottom view thereof;

FIG. 7 is a top view thereof; and,

FIG. 8 is a partial enlarged view of FIG. 2.
